(57) **CLAIM**

The ornamental design for a dental bib, as shown and described.

DESCRIPTION

FIG. 1 is an enlarged front perspective, partially exploded view of a dental bib showing my new design; the neck region shown partially opened;

FIG. 2 is a front view of the dental bib, the neck region shown closed and the bib laid flat;

FIG. 3 is a side view thereof;

FIG. 4 is a top view thereof; and,

FIG. 5 is a back view thereof.

The broken lines showing a surface pattern are for illustrative purposes only and form no part of the claimed design.
